UNITED STATES PATENT OFFICE

DORA F. BEAUCHAMP, OF NEW YORK, N. Y.

RETAINING AND SUSTAINING DEVICE

Application filed September 9, 1932. Serial No. 632,441.

This invention relates to a device which may be used in conjunction with a garment hanger, and which also may be used for hanging a garment.

5 One of the objects of the invention is the provision of a device of dual character in that it may be used in conjunction with a garment hanger to prevent the shoulder straps of the garment suspended from the hanger from slipping off the hanger, and which may be attached in closets, on doors or on walls for hanging a garment of a class having shoulder straps, such as women's décolleté gowns, slips, corselets, and also bathing suits and beach 10 pajamas and others.

Another object of the invention is the provision of a simple, inexpensive and practical device of the character mentioned.

The nature of the invention and its distinguishing features and advantages will appear when the following specification is read in connection with the accompanying drawing, in which

25 Figure 1 is a perspective view of a device constructed in accordance with the invention;

Figure 2 is a view showing two of the devices in use in conjunction with a conventional form of garment hanger;

30 Figure 3 is an enlarged section taken on the line 3/3 of Figure 2;

Figure 4 is a view showing two of the devices secured to a wall so as to co-operate with each other to hang a garment, a portion of which is indicated in dot and dash lines; and

Figure 5 is a view looking in the direction indicated by the arrows 5/5 appearing in Figure 4.

40 Referring now more particularly to the drawing, it will be apparent that the device includes two members 10 and 11 respectively. Each of these members may be made of any suitable material, such as a strip of textile material, a piece of tape, fibre or thin sheet metal. The member 10 has means at each end for the purpose of securing the member in place. The said means may be of any practical form, and in the present instance consists of a metal clip 12 which is clinched in

engagement with the end of the member 10, the said clip being provided with prongs 13. The member 11 has laterally projecting portions 14 on one end thereof. These portions 14 may be provided integral with the member 11, or may be provided by the use of a separate piece or strip of material secured to the member 11, as shown in the present instance. The portions 14 constitute means equivalent to the member 10. Each of the portions 14 on the outer extremity thereof has securing means similar to that on the member 10. Coactive means in the form of a separable fastener is employed to detachably or separably fasten the end of the member 11 remote from that having the portions 14 to the member 10 approximately centrally of the latter. In the present instance the said coactive means or separable fastener consists of snap fastener elements 15 and 16 secured respectively to the member 10 and said end of the member 11.

55 In accordance with the invention, two of the devices having the features aforesaid may be used in conjunction with a garment hanger 17, as shown in Figure 2. The two devices are attached respectively to the arms of the hanger 17. The member 10 of each device is wrapped or made to embrace the arm of the hanger, and the prongs 13 are impaled in said arm. The portions 14 of member 11 are similarly arranged on the arm of the hanger and the prongs 13 at the ends thereof being impaled in the arm of the hanger, as shown most clearly in Figure 3. 60 When the garment having shoulder straps is arranged on the hanger 17 each of these shoulder straps, designated 18, will be kept from slipping off the hanger by the member 11. By engaging the fastening elements 15 and 16 to secure the member 11 to the member 10, the shoulder straps 18 will be kept 65 in place and also from becoming separated from the hanger 17. In order to remove the garment from the hanger it is only necessary to separate the elements 15 and 16 after which the garment may be readily removed from the hanger. The device is also designed and adapted to be used for hanging a garment as 70 illustrated in Figure 4 of the drawing. Use 75 100

is made of two devices which may be attached to a wall, door or suitable support within a closet or locker by reason of the prongs 13. The shoulder straps of the garment may be engaged with the members 11 after which the said members 11 may be secured to the members 10 by reason of the fastener elements 15 and 16. To remove the garment it is only necessary to detach the members 11 from the members 10 by separating the elements 15 and 16, as will be readily understood.

I claim:

A device of the character described comprising two strip members of limp material

each having means on the opposite ends thereof for securing the strip members in spaced relation embracing the arm of a garment hanger, or for securing said strip members in spaced relation on a suitable substantially flat support, a third strip member of limp material, one end of said third strip member being secured to one of said two strip members, and coacting means on the remaining end of said third strip member and the other of said two strip members, to detachably secure said end thereto, whereby said third strip member may be engaged and disengaged for the purposes specified.
